5 Claims. (Cl. 123—169)

1

This invention relates to spark plug mechanism of the type intended for application to an internal combustion engine, and which forms an antechamber with respect to the engine's combustion space.

Many spark plugs and spark plug adaptors have been proposed heretofore of special design, intended to reduce the tendency of the spark plug to become fouled by the deposit of carbon and lead compounds from gasoline, as well as to reduce detonation, increase power and generally to improve combustion efficiency. Some of these proposed designs have been more effective than others.

The spark plug mechanism according to the present invention has proven to be particularly free from fouling or burning of the electrodes or short circuiting caused by deposit of carbon or lead compounds on the spark plug insulator and in its cavity. The engine operation temperature limit at which preignition will occur is greatly increased, yet the combustion is propagated through the combustible mixture in the engine's combustion space so effectively by the spark plug mechanism that an increase in power and engine efficiency is obtained while detonation is decreased. As a result of the more effective flame propagation, the engine can be started more easily and idles smoothly at lower speeds.

The spark plug mechanism of this invention is applicable to an internal combustion engine by being screwed into the usual spark plug hole, so that it does not require any modification of existing engines, although it may be built to fit various sizes of hole. Its structure, however, provides an antechamber within which the electrodes forming the spark gap are housed. The designation "spark plug mechanism" in this specification is intended to include both an arrangement in which the antechamber is formed in an adaptor to be screwed into the engine and into which a standard spark plug may be screwed, and also a spark plug which is itself specially formed in accordance with the invention.

In order to accomplish the advantages enumerated above it has been found that, within limits, the antechamber must have a certain shape, proportions and dimensions, and the electrodes forming the spark gap must be located in rather a particular position in the antechamber. Maximum effectiveness of the spark plug operation depends largely on a proper relation between various characteristics of the spark plug mechanism, and a nice balance of proportions and dimensions must be maintained between the parts of the spark plug mechanism.

2

More specifically, for maximum power and absence of detonation and preignition, the antechamber within the spark plug mechanism is convergent toward the inner end of the spark plug, which is the end to be exposed within the engine combustion chamber, and opens at such end through an aperture which must be sufficiently small as to produce the desired nozzle effect of gas moving into and out of the antechamber, yet not so small as to restrict excessively the passage of such gas or cause excessive velocities in the aperture. The electrodes forming the spark gap must be located sufficiently far from the inner end of the spark plug and the restricted opening of the antechamber as to be removed from direct contact with rich combustible mixture, to reduce the tendency for carbon and lead compound deposits to form, and preferably the space behind the electrodes is small and protected by a shoulder or step formation between it and the main portion of the antechamber.

Spark plug mechanisms may be classified as either of the hot type, where heat cannot be transmitted too readily from the metal and ceramic insulating material of the central electrode and core to the shell of the spark plug mechanism, or of the cold type where the metal and insulating material of the central electrode is in quite direct contact with the shell of the spark plug mechanism, so that heat will be dissipated readily from the core.

The spark plug mechanism of this invention has the unique advantage of permitting a very cold type of construction without the usual tendency toward excessive fouling.

Additionally, certain parts of the spark plug mechanism are shaped to be more effective. Thus the restricted opening from the antechamber through the inner end of the spark plug mechanism is rounded, flaring from the minimum opening to the inner end of the spark plug to promote smoothness of flow of the gas and minimum turbulence both when moving from the combustion space into the antechamber and when moving from the antechamber into the combustion space. Preferably also the antechamber converges toward the restricted opening and is faired into its wall, and such convergence is formed by concavely curved walls of the antechamber. All these features contribute to the effectiveness of the spark plug.

Critical dimensions and proportions of the spark plug mechanism will be pointed out in the following detailed description of representative forms shown in the accompanying drawings.

Figure 1 is a longitudinal sectional view through a spark plug constructed in accordance with the

invention, and Figure 2 is an exploded perspective view with portions broken away to show internal construction.

Figure 3 is a longitudinal sectional view of a spark plug and adaptor combination type of spark plug mechanism with parts broken away.

Figure 4 is a longitudinal sectional view through a further modification of the spark plug mechanism with parts broken away.

Figure 1 shows a spark plug incorporating the invention which is intended to be screwed directly into the spark plug hole or port of an internal combustion engine and incorporates an antechamber. The spark plug body includes a shell 1 having an externally threaded inner end portion 10 of a standard size to screw into the usual port or spark plug hole of an internal combustion engine. The external diameter of the thread on this part may, for example, be eighteen millimeters. At the outer end of this threaded portion is an external shoulder 11, and slightly farther from the inner end 16 of the spark plug, that is the end adapted to be exposed within the engine's combustion space, is an internal shoulder 12. Near the outer end of the shell 1 is a noncircular portion 13, preferably hexagonal, to which a wrench may be applied for screwing the threaded portion 10 into an engine port or for unscrewing the plug from the engine port.

Within the shell 1 is received a bushing 2, completing the plug body, having a step 20 approximately midway between its ends which bears against the internal shoulder 12 of the shell. The shell may have a further slight shoulder 14 against which the inner end of bushing 2 seats, such inner bushing end being located at least substantially as close to the inner end 16 of the plug body as the outer end of the threaded portion 10. Preferably this bushing is metal and its axially inner end carries the grounded electrode 21 located immediately adjacent to the inner end face of the bushing.

The central electrode 3 is mounted in a ceramic spindle 30 carrying a metal band 31 threaded externally to mesh with internal threads formed in the outer end of the shell 1. A spacing washer 4 is interposed between the band 31 and the outer end of bushing 2, which is of selected thickness to establish the proper width of the spark gap between the grounded electrode 21 and the central electrode 3. The outer end of the band 31 has a suitable formation 32 to receive a wrench operable to rotate the spindle 30 relative to the shell.

The outer end of the shell 1 is closed by a cap 5 having an externally threaded inner end complementary to the internal thread of the shell. Outwardly of this threaded end portion the sleeve has a noncircular wrench-engaging part 50 which preferably is hexagonal. This cap has a ceramic lining 51, insulating the cap and shell from the terminal 33 on the outer end of the spindle 30. The outer end of the cap is open for reception of an electrical conductor to engage the terminal 33, and preferably has external threads 52 to receive a protective cap or for securing of an ignition wire shield.

Of the parts described above the spindle 30, central electrode 3 and terminal 33, and the cap 5, may be conventional. The invention of the present spark plug mechanism resides in the antechamber formation within the spark plug body composed of the shell 1 and bushing 2, and the relationship of the electrodes 3 and 21 and

the inner end of spindle 30 relative to such antechamber.

The formation of the antechamber within the inner end portion of the body includes a large portion and a restricted opening through the inner end 16 of shell 1, such opening affording communication between the large portion of the antechamber and the combustion space of the internal combustion engine. The inner walls of such large antechamber portion converge from a maximum diameter or cross sectional zone 15 toward a minimum diameter or cross sectional portion 17 in the restricted opening. Such convergent walls preferably are concave and are reasonably faired into the restricted orifice or minimum cross sectional portion 17 to promote smooth flow of gas in either direction between these two portions. While neither the degree nor curvature of the antechamber wall is critical, such curvature may conveniently be of circular arcuate shape, a diameter of the maximum cross sectional portion of the antechamber substantially coinciding with a radius of such circular arc, and the radius of such arc preferably being of a length approximately three times as great as the radius of the maximum cross-sectional portion of the antechamber, as shown in Figures 1 and 3. Preferably the antechamber is of circular cross section, but it may be noncircular, in which case the word "diameter" as used in this description will be understood to indicate the transverse width of the antechamber. Additionally, the orifice flares from its minimum cross sectional portion toward the inner end 16 of the spark plug, preferably in a smooth curve, again to reduce the turbulence of flow from the engine's combustion space into the orifice or from the antechamber through the orifice into the engine's combustion space. Such construction eliminates sharp corners which otherwise might be heated to incandescence and cause preignition.

Immediately at the side of the large portion of the antechamber away from the inner end 16 of the spark plug body the axially inner end of bushing 2 forms a radially inwardly projecting shoulder in the antechamber. The electrodes 21 and 3 are located substantially at such shoulder, Fig. 3 showing the gap coplanar with such shoulder and Figs. 1 and 4 showing the gap immediately at the side of such shoulder away from the orifice and body end 16, that is axially outward from such shoulder, and within a reduced bore portion 22 of the bushing.

The inner end of the insulating spindle 30 is tapered inwardly, and in order to provide sufficient clearance between the bushing 2 and spindle the bore of the bushing has an enlarged portion 23 toward its axially outer end, i. e. the bore portion 22 at the inner end of such bushing is stepped radially inward toward the spindle porcelain to reduce the space around its inner end. The lengths and diameters of the parts of this stepped bore should be related to the lengths and diameters of corresponding portions of the inner end of spindle 30 so that sufficient clearance will be left between the two at all locations axially of them to accommodate some deposit of carbon and lead compounds from the fuel, while this space is narrow enough to keep the portion of the antechamber outwardly of the spark gap of small volume as compared to the volume of the antechamber inwardly from the spark gap.

If the inner end orifice of the antechamber is

too restricted for the size of the antechamber as a whole, the desired functioning of the spark plug mechanism will be lost. Consequently it will be helpful to describe an example of a typical spark plug mechanism made in accordance with the present invention of a size suitable for installation in present engines. In a so-called "18 millimeter spark plug" the external diameter of the threads 10 on the inner end portion of the spark plug would be 18 millimeters. The minimum diameter of the restricted orifice 11 forming the inner end of the antechamber in such case should not be less than three-sixteenths of an inch in order to enable sufficient gas to flow from the engine combustion space into the antechamber and out again. On the other hand, if the minimum diameter of such orifice 11 is more than about three-eighths of an inch, the desired nozzle effect would not be secured and excessive fouling caused by deposit of carbon and lead compounds in the antechamber would occur.

The maximum diameter of the large portion of the antechamber 15 may be from seven-sixteenths of an inch to nine-sixteenths of an inch, an appreciable reduction below the former value increasing the tendency for carbon and lead compounds to be deposited in the antechamber, and any appreciable increase above the latter dimension causing excessive reduction in the power produced by the engine. The curved surfaces 18 may be of circular arcuate shape having a radius of approximately three-fourths of an inch and centers in the plane defined by the shoulder formed by the inner end of bushing 2. In such a spark plug it will be seen that the minimum orifice diameter is between one-third and two-thirds of the diameter of the maximum cross section of the antechamber.

In an 18 millimeter spark plug having a restricted orifice minimum diameter of one-fourth inch and one-half inch as a maximum diameter of the antechamber, the total volume of the antechamber progressively tapered in cross section toward such orifice with walls of circular arcuate curvature as described above was 0.0975 cubic inch and the area of the restricted orifice 0.049 square inch. This gives a volume to area ratio of approximately two, where the volume of the antechamber is in terms of cubic inches and the minimum cross section of the restricted orifice is given in square inches. A ratio of volume to area of this order has resulted in an excellent spark plug mechanism, whereas if the volume of the antechamber is increased substantially without an increase in the size of orifice, some loss in engine power occurs, and at high power excessive heating may cause preignition. On the other hand, if the volume of the antechamber is reduced substantially below this ratio without change in minimum area of the orifice the electrodes will be exposed to excessive heat, causing them to burn off comparatively quickly, and the antechamber will tend to become fouled by deposit of carbon and lead compounds.

Efficiency of the spark plug is prejudiced by making the orifice 11 at the inner end of the antechamber either too small or too long. Preferably the aperture flares in both directions from the minimum diameter section. In addition for at least sixty percent of the length of the antechamber between its zone of maximum cross section 15 and the inner end 16 of the spark plug the diameter of the antechamber should be at least sixty percent of the maximum diameter. Also

the electrodes must be remote from the restricted orifice of the antechamber at the inner end of the spark plug and substantially at the inwardly projecting shoulder of the antechamber, the spacing between the orifice portion of minimum cross section and such shoulder being at least one and one-half times the diameter of such minimum cross-sectional portion.

To reduce the tendency of carbon and lead compounds to be deposited in the space radially outwardly of the spark gap, which would tend to cause a short circuit, the volume of that portion of the antechamber axially outwardly of the spark gap should be a minor portion of the volume of the entire antechamber. In fact, the volume of that portion of the antechamber axially outwardly of the zone of maximum cross section of the antechamber should be a minor portion of the volume of the entire antechamber. Conversely, of course, that portion of the antechamber between the zone of maximum cross section and the inner end 16 of the spark plug has a volume which is a major portion of the entire volume of the antechamber. In a spark plug of this type it is also preferred that the grounded electrode 21 project radially into a position overlapping the central electrode, as shown in Figures 1 and 4. It is possible, however, to employ electrodes of other types, such, for example, as that shown in Figure 3, because of the noncritical location of the electrodes, so long as they are remote from the aperture 17 and at or adjacent to the inwardly projecting shoulder of the antechamber.

Features of the spark plug shown in Figure 1 may be incorporated in an adaptor and spark plug combination, as shown in Figure 3. In this structure the proportions and dimensions of the antechamber from its portion of maximum cross section 15 toward its inner end 16 are all the same as in Figure 1, and are numbered correspondingly. The shoulder 14' of the adaptor shell may be a little wider than the corresponding shoulder in Figure 1, and the bore of the shell is threaded internally from its outer end down to this shoulder to receive the complementally threaded inner end of the shell 6 of a conventional spark plug. The inner end of such spark plug shell then forms the shoulder corresponding to the shoulder formed by the inner end of bushing 2 in the spark plug of Figure 1, and the adaptor shell and spark plug shell together form the body of the spark plug mechanism. Instead of the wall of the adaptor shell 1 being as long as the shell 1 in Figure 1, its entire portion 13' outwardly of its inner threaded end portion 10, which extends from the inner end of the adaptor body to a location beyond the shoulder 14' and the inner end of the spark plug, may be of non-circular shape, such as hexagonal, to receive a wrench for inserting or removing the adaptor. The spark plug shell also may have a non-circular portion 60, such as of hexagonal shape, which can be gripped by a wrench for assembly of the spark plug and adaptor.

The central electrode 3, its spindle 30, boss 34, gasket 35, and retaining nut 36 threaded into an internal thread of the spark plug shell 6 may all be conventional. Also, the complemental shapes of the inner end of the spindle 30 and the bore of the inner end portion of the spark plug shell 60 may be conventional. In fact the spark plug of Figure 3 may be of a standard type in its entirety, for example a small size, 14 millimeter, spark plug, or, if the wall thickness of the

adaptor 1 is increased, a 10 millimeter spark plug.

In view of the similarity of shape, proportions and dimensions of the various parts of the spark plug and adaptor combination shown in Figure 3 to those of the spark plug shown in Figure 1, detailed description of these features need not be duplicated.

In Figure 4 a modification is shown in which the element forming the shoulder in the antechamber is integral with the shell. In this instance the shell 1" has the thread 10' on its inner end portion extending from its inner end substantially to the inner end of the antechamber proper at shoulder 14", and the walls 18 of the cavity are curved between the maximum cross-sectional portion 15 and the minimum cross-sectional portion 17 of the restricted orifice, as in the form shown in Figure 1. Other parts are numbered correspondingly. The principal difference lies in the shoulder 14" facing axially inward, instead of axially outward like the shoulder 14 of the spark plug in Figure 1. The cavity 22' is thus formed in the shell itself rather than in a bushing inserted into the sleeve. Also, the noncircular portion 13", corresponding to the hexagonal portion 13 of Figure 1, is closer to the inner end 16 of the spark plug.

The spark plug mechanisms shown in Figures 1 and 3 are nominally of the hot type because of the spacing between the central electrode spindle 30 and encircling spark plug body extending a considerable distance from the end of the spindle tip. In Figure 4 a spark plug of the cold type is shown, in which the end of the insulating spindle 30' radially inwardly of the enlargement 34 is shorter than in the other forms shown and has a shoulder 37 which bears against a gasket 35 close to the bore 22'. Consequently, there is a shorter path for heat to be conducted from the core for dissipation through the threaded portion 10' of the spark plug into the engine than in the other types of plug shown, and there is less core surface subjected to the heat of combustion. Outwardly of the enlargement 34 is the retaining nut 36 screwed into internal threads in the shell 1" in the same manner that the nut 36 is secured in the shell 6 of the spark plug shown in Figure 3.

Actually the core of the spark plug shown in Figure 1 may be cooler than the core of a spark plug such as shown in Figure 4 since heat cannot be conducted readily between the bushing 2 and the body 1 of this spark plug because of the discontinuity of these parts. The threaded engagement between the metal portion 31 of the spark plug core and the body 1 provides a better heat conducting path than between the bushing and the body. Consequently, heat may flow from the ceramic core in Figure 1 through the threaded connection between the part 31 and the body 1, and down to the threads 10 for dissipation into the engine more readily than heat can flow from the bushing 2 to the body 1. While the inner end of the core spindle 30 will still probably be somewhat hotter than the bushing 2, it will be cooler than if this bushing were formed integral with the spark plug body, and the cooler the core tip the less will be the tendency for pre-ignition to occur. At the same time, because of the long space between the spindle tip and bushing, the less chance is there for fouling and shorting out of the plug, despite accumulation of lead and carbon in this space. By keeping such space to a minimum volume by provision of the step in the bushing formed by the reduced bore 22

around the core tip, the less unburned fuel can penetrate into this space from which carbon and lead can be deposited. This construction, therefore, reduces fouling to a minimum without corresponding increase in the tendency for pre-ignition to occur, which normally would result from the use of a hot type spark plug construction in such a situation.

The precise action in operation of the spark plug mechanism described is not known, although the general results of a minimum accumulation of fouling deposits of carbon and lead compounds in the antechamber even during operation at high speeds over extended periods, increased power, reduced detonation, easier starting, smoother and longer idling, and more efficient fuel combustion than obtained with other types of spark plugs, have been ascertained by tests. It is believed that during compression combustible mixture flowing from the engine through the restricted orifice into the enlarged portion of the antechamber will remain in a stratum rather definitely segregated from a stratum of burned mixture in the vicinity of the electrodes. Consequently the electrode vicinity will be comparatively free from liquid or gaseous materials from which carbon or lead compounds may be precipitated onto the walls of the antechamber. The amount of combustible mixture actually entering the antechamber will depend somewhat on the capacity and compression ratio of the engine's combustion chamber.

Even at completion of the compression stroke, presumably because of the absence of appreciable turbulence in the antechamber, the combustible mixture will be very lean in the enlarged portion of the antechamber, and may be progressively leaner from the restricted orifice toward the electrodes. Adjacent to the electrodes the mixture need only be sufficiently concentrated to ignite and initiate the burning of the mixture in the antechamber, for projection of a flame into the engine's combustion space. Any deposit of carbon and lead compounds on the walls of the antechamber around or axially outwardly of the electrodes is consequently very small, but after extended use of the spark plug some deposit occurs in the portion of the antechamber between the electrodes and the spark plug's inner end. Such deposit is found to be graduated axially, being heavier at the inner end of the spark plug and progressively lighter toward the electrodes, apparently corresponding to the fuel to air ratio variation axially of the antechamber.

When the mixture within the antechamber is ignited, a tongue of flame will be projected through the restricted orifice into the combustible mixture within the engine's combustion space to propagate combustion rapidly and thoroughly throughout such space. Because of the projection of such a tongue of flame into the combustion space, a leaner mixture can be satisfactorily ignited than can be ignited by a spark gap alone. The greater power and efficiency of the engine presumably results from more complete combustion of the mixture.

I claim as my invention:

1. A spark plug comprising a body having an internal chamber of circular cross section, an internal shoulder in said chamber facing toward the inner end of said body, the walls of said chamber being of circular arcuate shape in an axial direction and converging from said internal shoulder toward the inner end of the said body, the radius of curvature of said walls being

approximately three times the maximum radius of said chamber, and the centers of curvature of axial wall elements being substantially in the plane of said internal shoulder, said body having an opening from said internal chamber through the body's inner end, an insulator supporting a first electrode within said body and disposed adjacent to said internal shoulder, a second electrode electrically connected to said body, cooperating with said first electrode and disposed adjacent to said internal shoulder, and an external shoulder on said body facing toward the inner end of said body and spaced therefrom a distance at least substantially as great as the distance between said internal shoulder and the inner end of said body, and said body being externally threaded from its inner end substantially to said external shoulder for reception in the spark plug port of an engine.

2. A spark plug comprising a body having an internal chamber, an internal shoulder within said chamber facing toward the inner end of said body, said internal chamber flaring away from the inner end of said body and having an opening through the body's inner end of a minimum width greater than its axial extent from the inner end of the body to the flaring chamber, an insulator supporting a first electrode within said body and disposed adjacent to said internal shoulder, and a second electrode electrically connected to said body, cooperating with said first electrode and disposed adjacent to said internal shoulder, said body and said insulator being spaced apart and thereby forming therebetween an annular space at the side of said internal shoulder remote from the inner end of said body of an axial extent at least substantially as great as the distance between said internal shoulder and the inner end of said body.

3. A spark plug comprising a body having an internal chamber, an internal shoulder within said chamber facing toward the inner end of said body, said body having an opening from said internal chamber through the body's inner end of a minimum area between one-ninth and one-half of the maximum cross-sectional area of said internal chamber, an insulator disposed centrally within said body supporting a first electrode within said body and disposed adjacent to said internal shoulder, and a second electrode electrically connected to said body, cooperating with said first electrode and disposed adjacent to said internal shoulder, said body and said insulator being spaced apart and thereby forming a narrow annular portion of said internal chamber of an axial extent at the side of said internal shoulder remote from the inner end of said body at least substantially as great as the distance between said internal shoulder and the inner end of said body and of a volume a minor portion of the total volume of said internal chamber, and an external shoulder on said body facing toward the inner end of said body and spaced therefrom a distance at least substantially as great as the distance between said internal shoulder and the inner end of said body, and said body being externally threaded from its inner end substantially to said external shoulder for reception in the spark plug port of an engine.

4. A spark plug comprising a body having an

internal chamber, an internal shoulder within said chamber facing toward the inner end of said body, said body having an opening from said internal chamber through the body's inner end of a minimum area between one-ninth and one-half of the maximum cross-sectional area of said internal chamber, an insulator disposed centrally within said body supporting a first electrode within said body and disposed adjacent to said internal shoulder, and a second electrode electrically connected to said body, cooperating with said first electrode and disposed adjacent to said internal shoulder, said body and said insulator being spaced apart and thereby forming a narrow annular portion of said internal chamber at the side of said internal shoulder remote from the inner end of said body of a volume a minor portion of the total volume of said internal chamber, the peripheral extent of that portion of said chamber formed by said internal shoulder being less than the peripheral extent of a portion of said internal shoulder being less than the peripheral extent of a portion of said internal shoulder more remote from the inner end of said body.

5. A spark plug comprising a body having an internal chamber, an internal shoulder within said chamber facing toward the inner end of said body, said body having an opening from said internal chamber through the body's inner end of a minimum area between one-ninth and one-half of the maximum cross-sectional area of said internal chamber, an insulator disposed centrally within said body supporting a first electrode within said body and disposed adjacent to said internal shoulder, and a second electrode electrically connected to said body, cooperating with said first electrode and disposed adjacent to said internal shoulder, said body and said insulator being spaced apart and thereby forming a narrow annular portion of said internal chamber at the side of said internal shoulder remote from the inner end of said body of a volume a minor portion of the total volume of said internal chamber, the peripheral extent of that portion of said chamber formed by said internal shoulder being less than the peripheral extent of a portion of said internal shoulder more remote from the inner end of said body.
